J. W. Patterson

James D. Marsh

UNITED STATES PATENT OFFICE.

JAMES PATERSON, OF ELIZABETH, NEW JERSEY, ASSIGNOR TO DEBORAH POWERS, ALBERT E. POWERS, AND NATHANIEL B. POWERS, OF LANSINGBURG, NEW YORK.

DESIGN FOR A FLOOR-CLOTH PATTERN.

Specification forming part of Design No. 1,582, dated May 20, 1862.

To all whom it may concern:

Be it known that I, JAMES PATERSON, of the city of Elizabeth, in the county of Union and State of New Jersey, have invented or produced a new Design or Figure for Printing or Stamping upon Floor Oil-Cloths or other Fabrics; and I do hereby declare that the following is a full and exact description of the same.

The pattern consists in its general features of four squares, three of which are unlike, viz: No. 1 is of white, with a smaller square of dark color placed upon it diamondwise, which smaller square is ornamented with fretwork in two colors. No. 2 is made up wholly of fretwork disposed diamondwise of the square. No. 3 is divided into four parts by diagonal lines, and a small square placed diamondwise in the center, the opposite parts being of like color and the adjoining parts of unlike color.

No. 4 is like No. 3, except in the manner of placing the colors. The diagonal lines are so disposed in connection with the small squares upon the centers of Nos. 3 and 4 as to cause No. 1, with the adjoining parts of Nos. 3 and 4, to form a square with re-entrant angles disposed diamondwise of the pattern, and the like effect with No. 2 and the adjoining parts of Nos. 3 and 4.

What I claim as my invention, and desire to secure by Letters Patent, is—

The pattern or design for floor oil-cloths, as set forth and described in the foregoing specification and shown upon the accompanying drawing, which is hereby referred to and declared to be a part of this specification.

JAS. PATERSON.
